UNITED STATES PATENT OFFICE.

MARGARET I. MUNCE, OF WASHINGTON, PENNSYLVANIA.

PROTECTOR FOR CLOSET-SEATS.

1,368,825.

Specification of Letters Patent. Patented Feb. 15, 1921.

Application filed September 23, 1920. Serial No. 412,282.

To all whom it may concern:

Be it known that I, MARGARET I. MUNCE, a citizen of the United States, and a resident of Washington, in the county of Washington and State of Pennsylvania, have invented certain new and useful Improvements in Protectors for Closet-Seats; and I do hereby declare the following to be a full, clear, and exact description of the invention, such as will enable others skilled in the art to which it appertains to make and use the same.

My invention consists of a protector formed of any suitable material (preferably of a good heavy grade of tissue-paper), and may be made in one or more pieces and of any suitable contour, having an opening in the center thereof.

Secured to one side of the protector is a cord or string, the object of which will be more fully described hereinafter.

The drawing shows a plan view of the invention and the parts thereof are represented by the reference letters A and B. A 25 represents the protector and B, the cord or string.

The object of the cord or string is for

convenience in removing the protector from the closet seats after it has been used, the hands not coming into contact with the protector proper, thus making a perfectly sanitary article.

The protectors may be folded and placed into packages containing any desired number for convenience in carrying them.

I am aware that protectors of this sort have been made of tissue-paper, but with the addition of the cord or string, I have increased the sanitation.

Having described my invention what I claim is:

A new article of manufacture comprising a tissue-paper protector for closet seats, and a cord or string secured to one side thereof, all substantially as shown and for the purpose described.

In testimony that I claim the foregoing as my own invention, I have hereunto set my hand in the presence of two subscribing witnesses.

MARGARET I. MUNCE.
